UNITED STATES PATENT OFFICE.

ERNST PETERSSON, OF OREBRO, SWEDEN.

MOLD.

Application filed May 28, 1926, Serial No. 112,389, and in Sweden July 19, 1924.

- This invention relates to molds, particularly adapted for casting iron and other difficultly fusible metals by forcing the molten metal into the mold by vacuum.
- The object of the invention is to effect such an automatic movement of the parts of the mold as to cause said parts to move in a certain order towards the nozzle of the casting pipe and simultaneously towards each other and then away from the said nozzle and away from each other, the casting being effected during the former period and the cast object being delivered during the latter period.
- 15 The invention consists essentially in this that two jaws, movably arranged in a suitable frame and to which the parts of the mold are secured, are connected to a driving device and guided in such way as to obtain a uniform automatic movement, by which they alternately close and open the mold and simultaneously in the former case press the mold against the nozzle of the casting pipe and in the latter case remove the mold from the said nozzle, said jaws being movably arranged in a direction towards and away from each other in a slide displaceable in the frame and to which the driving means is connected. The driving means may preferably consist of a rotary disk having an eccentrically mounted journal or a crank engaging a slot made in the slide and extending at right angles to the direction of movement of the slide.
- 25 30 35 40 45 50 55 60 65 70 75 80 85 90 95 100
- The slide moves towards and away from the nozzle of the casting pipe, when rotating the disk and the eccentrically mounted journal, and the jaws follow the movement of the slide, in which they are capable to slide towards and away from each other. By providing the jaws with surfaces inclined to the direction of movement of the slide and by causing said surfaces to slide against corresponding inclined surfaces in the frame of the machine, the combined movement will be obtained, which simultaneously closes the mold and presses it against the nozzle of the casting pipe or opens the mold and removes it from said nozzle.
- 50 In the annexed drawing three forms of embodiment of the invention are shown, Figs. 1, 2 and 3 showing plane views of

the different forms of embodiment, respectively.

Referring to Fig. 1, 1 designates the two jaws placed horizontally in a suitable frame 2. The movements of the jaws are effected by means of a slide 3, which is in turn driven by a rotary disk 4 having an eccentrically disposed journal 5. The said journal 5 extends into a transversal slot in the slide 3, and when moving the journal 5 in a circular path by rotating the disk 4, the slide 3 is moved in the direction towards and away from the casting nozzle 6. The jaws 1 are guided by the slide 3 in such manner as to be capable of sliding towards and away from each other. In order to obtain the combined movements of the jaws 1 so as to simultaneously close the mold 7 and press it against the nozzle 6 or to open the mold 7 and remove it from the nozzle, the jaws are provided with inclined surfaces 8 sliding against correspondingly shaped shoulders 9 formed in or secured to the frame 2.

Fig. 2 shows a form of embodiment of the invention, in which the jaws 1 are provided with straight slots 10 directed angularly to the direction of movement of the slide 3, pins 11 or the like secured to the frame 2 meshing with said slots 10.

According to the form of embodiment shown in Fig. 3, the jaws 1 are provided with somewhat curved slots 10, placed obliquely with relation to the direction of movement of the slide 3, pins 11 or the like secured to the frame 2 meshing with said slots 10, thus causing the jaws 1 to move towards and away from each other when moving them towards and away from the nozzle 6, respectively.

What I claim as new and desire to secure by Letters Patent of the United States of America is:—

1. In a casting machine, particularly adapted for casting iron and other difficultly fusible metals by forcing the molten metal from the metal bath by vacuum, the combination of a casting nozzle, a divided mold, a number of jaws carrying the parts of said divided mold, a slide to which said jaws are movably connected, a frame in which said slide is movable in a direction towards and away from said nozzle, means for moving

said slide, and means for guiding said jaws so as to automatically close the divided mold when moving the slide and the jaws in the direction towards the nozzle and to automatically open said mold when moving the slide and the jaws away from said nozzle.

2. In a casting machine, particularly adapted for casting iron and other difficultly fusible metals by forcing the molten metal

10 from the metal bath by vacuum, the combination of a casting nozzle, a divided mold, a number of jaws carrying the parts of said divided mold, a slide to which said jaws are movably connected, a frame in which said

15 slide is movable in a direction towards and away from said nozzle, means for moving said slide, and means for guiding said jaws so as to automatically close the divided mold when moving the slide and the jaws in the direction towards the nozzle and to automatically open said mold when moving the slide and the jaws away from said nozzle, the means for moving said slide comprising an eccentric device co-operating with a slot in

20 said slide, said slot extending transversely with respect to the direction of movement of the slide.

3. In a casting machine, particularly adapted for casting iron and other difficultly fusible metals by forcing the molten metal

30 from the metal bath by vacuum, the combination of a casting nozzle, a divided mold, a number of jaws carrying the parts of said divided mold, a slide to which said jaws are movably connected, a frame in which said

35 slide is movable in a direction towards and away from said nozzle, means for moving said slide, and means for guiding said jaws so as to automatically close the divided mold

40 when moving the slide and the jaws in the direction towards the nozzle and to automatically open said mold when moving the slide and the jaws away from said nozzle, said latter means comprising sliding sur-

45 faces formed on said jaws and inclined with relation to the direction of movement of the jaws and co-operating with guiding means secured to said frame.

4. In a casting machine, particularly adapted for casting iron and other difficultly fusible metals by forcing the molten metal

50 from the metal bath by vacuum, the combination of a casting nozzle, a divided mold, a number of jaws carrying the parts of said divided mold, a slide to which said jaws are movably connected, a frame in which said

55 slide is movable in a direction towards and away from said nozzle, means for moving said slide, and means for guiding said jaws so as to automatically close the divided mold when moving the slide and the jaws in the direction towards the nozzle and to automatically open said mold when moving the slide and the jaws away from

60 said nozzle, said latter means comprising

sliding surfaces formed on said jaws and inclined with relation to the direction of movement of the jaws and co-operating with guiding means secured to said frame, and the means for moving the slide comprising 70 an eccentric device co-operating with a slot in said slide, said slot extending transversely with respect to the direction of movement of the slide.

5. In a casting machine, particularly 75 adapted for casting iron and other difficultly fusible metals by forcing the molten metal from the metal bath by vacuum, the combination of a casting nozzle, a divided mold, a number of jaws carrying the parts of said

80 divided mold, a slide to which said jaws are movably connected, a frame in which said slide is movable in a direction towards and away from said nozzle, means for moving said slide, and means for guiding said jaws so as to automatically close the divided mold

85 when moving the slide and the jaws in the direction towards the nozzle and to automatically open said mold when moving the slide and the jaws away from said nozzle, 90 said latter means comprising slots made in said jaws and inclined with relation to the direction of movement of the jaws and co-

95 operating with pins sliding in said slots and secured to said frame.

6. In a casting machine, particularly adapted for casting iron and other difficultly fusible metals by forcing the molten metal from the metal bath by vacuum, the combination of a casting nozzle, a divided mold, a number of jaws carrying the parts of said

100 divided mold, a slide to which said jaws are movably connected, a frame in which said slide is movable in a direction towards and away from said nozzle, means for moving said slide, and means for guiding said jaws so as to automatically close the divided mold

105 when moving the slide and the jaws in the direction towards the nozzle and to automatically open said mold when moving the slide and the jaws away from said nozzle, 110 said latter means comprising slots made in said jaws and inclined with relation to the direction of movement of the jaws and co-

115 operating with pins sliding in said slots and secured to said frame, and the means for moving the slide comprising an eccentric device co-operating with a slot in said slide, 120 said slot extending transversely with respect to the direction of movement of the slide.

7. In a casting machine, particularly adapted for casting iron and other difficultly fusible metals by forcing the molten metal from the metal bath by vacuum, the combination of a casting nozzle, a divided mold, a number of jaws carrying the parts of said divided mold, a slide to which said jaws are movably connected, a frame in which said slide is movable in a direction towards and 130

away from said nozzle, means for moving said slide, and means for guiding said jaws so as to automatically close the divided mold when moving the slide and the jaws in the direction towards the nozzle and to automatically open said mold when moving the slide and the jaws away from said nozzle, said latter means comprising slots made

in said jaws and inclined with relation to the direction of movement of the jaws and 10 co-operating with pins sliding in said slots and secured to said frame, said slots being curved.

In testimony whereof I affix my signature.

ERNST PETERSSON.
